Atty.

UNITED STATES PATENT OFFICE.

THOMAS A. LEGGE, OF CHICAGO, ILLINOIS, ASSIGNOR TO THE ADAMS & WESTLAKE COMPANY, A CORPORATION OF ILLINOIS.

BERTH LAMP.

1,404,980.

Specification of Letters Patent. Patented Jan. 31, 1922.

Application filed August 7, 1920. Serial No. 401,982.

To all whom it may concern:

Be it known that I, THOMAS A. LEGGE, a citizen of the United States, and resident of Chicago, county of Cook, and State of Illinois, have invented certain new and useful Improvements in Berth Lamps, of which the following is a specification and which are illustrated in the accompanying drawings, forming a part thereof.

10 The invention relates to berth lamps for use in sleeping cars and similar situations, and of the type comprising an openable door or panel carrying the lamp and provided with switch mechanism for closing 15 the circuit upon the opening of the door.

The object of the invention is to provide, in a device of this character, an improved 20 formed of switch mechanism which will be more certain in its action than the switches 20 which have heretofore been employed.

The invention consists of a device such as is illustrated in the accompanying drawings, in which—

Fig. 1 is a rear elevation of the lamp in 25 open or operative position;

Fig. 2 is a plan section on the line 2—2 of Fig. 1;

Fig. 3 is a side elevation of the lamp in 30 closed or inoperative position; and

Fig. 4 is a plan section on the line 4—4 of Fig. 3.

The invention is shown in connection with the berth lamp forming the subject of Letters Patent No. 942,963, of December 14, 35 1909, to William S. Hamm & Thomas A. Legge, but is applicable to lamps of other forms having an openable bulb-carrying door.

There is shown at 10 a frame adapted 40 to be secured to a wall and to bound an aperture therein. Within this frame there is pivotally mounted a member comprising two rigidly connected plates 11, 12, the former for closing the frame aperture when 45 the lamp is not in use, and the other for closing such aperture when the lamp is in service. A plate 13 is mounted at the upper margins of the two plates 11 and 12, for carrying a bulb socket 14. A spring, as 15, 50 reacts between the door and the frame for normally throwing the lamp to service position, the door being held in closed position by means of a suitable latch, as shown at 16, controlled by a push button 17.

55 The leading-in wires are shown at 18, 19,

and are connected, respectively, to binding posts 20, 21, fixedly attached and suitably insulated from the inner face of the frame 10, one of these binding posts being located preferably at the top and bottom of the 60 frame. Each of these binding posts comprises one element of the switch mechanism.

As most plainly shown in Fig. 2, these binding posts may conveniently be formed of a piece of sheet metal 22, attached to a 65 block of insulating material 23, which in turn is secured to the frame 10, one end of the element 22 being folded outwardly and inclined backwardly, as shown at 24, the wire-retaining screw 25 being set through 70 a portion thereof which is bent inwardly toward the insulating block.

The two ends 26, 27, of the local or lamp circuit are attached one to each of a pair of plungers 28, 29, slidably mounted in 75 brackets 30, 31, secured, respectively, to the inner faces of upwardly and downwardly projecting extensions, as 32, of the plate 12, a suitable insulating block, as 33, being interposed.

80 The plungers 28, 29, are thus aligned with the switch elements associated with the line binding posts, and the forward end of each of these plungers is turned outwardly at an inclination corresponding with 85 that of the element 24, as shown at 34. An expansion spring 35 is coiled about each of the plungers 28, 29, reacting between a shoulder thereon and the bracket by which the plunger is carried.

90 The parts are so positioned and proportioned that as the door swings outward to bring the lamp into service position the outwardly inclined end 34 of each of the plungers makes sliding contact with the 90 switch element 24 and the plunger is forced backwardly against the resistance of the spring 35.

100 Openable berth lamps are subjected to severe usage, and experience has shown that switch elements formed of resilient material become distorted and bent by violent slamming of the door, and their action is rendered uncertain, also, by the sagging of the door due to wear or distortion of its pivots. 105

110 In the device herein shown and described the engaging elements of the switch are rigid, the movement of the plunger is very slight, and the spring will withstand any amount of jarring or slamming to which

the lamp may be subjected. The contacting faces of the switch elements may be of sufficient width to insure proper engagement, regardless of the condition of the 5 door pivots.

While a practical and preferred form of construction is shown and described, various changes of detail may be made without departing from the scope of the invention.

10 I claim as my invention—

1. In a berth lamp in combination, a frame, a door pivotally mounted on the frame, a pair of line circuit terminals on the frame, each terminal comprising a switch element, 15 a lamp socket carried by the door, a pair of spring-advanced plungers carried by the door each electrically connected to the socket circuit and positioned to slidably engage the switch element of one of the line terminals.

2. In a berth lamp, in combination, a frame, a door pivotally mounted on the frame, a line circuit terminal on the frame and comprising a switch element, a lamp 25 socket carried by the door and having a local circuit, a slideable spring-advanced switch element carried by the door and electrically connected with the local circuit and positioned to make a wiping contact 30 with the first-named switch element in one position of the door.

3. A berth lamp comprising, in combination, a frame, a door pivotally mounted on the frame, a lamp carried by the door, a local circuit for the lamp, a terminal 35 mounted on the frame at each end of the door, each terminal connected to one side of a line circuit, a contact surface on each terminal lying in a plane parallel with the pivotal axis of the door and forming an 40 acute angle with the plane of the door frame, and a resiliently yielding terminal connected with each side of the local circuit and carried by the door, said terminals each adapted to make wiping contact with one of said 45 surfaces.

4. A berth lamp comprising, in combination, a frame, a door pivotally mounted on the frame, a local lamp circuit carried by the door, terminals mounted on the frame 50 one at each end of the door connected each to one side of the line circuit, a contact surface on each terminal lying in a plane parallel with the pivotal axis of the door forming an acute angle with the plane of 55 the door frame and sloping away from the free edge of the door when the door is closed, local circuit terminals carried by the door, one making a wiping contact with each of said surfaces and resiliently pressed 60 thereagainst.

THOMAS A. LEGGE.
